UNITED STATES PATENT OFFICE.

FRANK W. EAGELSTON, OF BERKELEY, CALIFORNIA.

PROCESS AND MEANS FOR SWITCHING RAILROAD CARS.

Application filed February 11, 1922. Serial No. 535,778.

To all whom it may concern:

Be it known that I, FRANK W. EAGELSTON, a citizen of the United States, and a resident of Berkeley, in the county of Alameda 5 and State of California, have invented a new and useful Improvement in Processes and Means for Switching Railroad Cars, of which the following is a full, clear, and exact description.

10 My invention relates to improvements in the process and means for switching railroad cars, and it consists in the steps herein-after disclosed, and in the combinations, constructions, and arrangements herein described and claimed.

An object of my invention is to provide a process for switching cars, such as railroad cars, which will greatly relieve congestion at terminals or yards.

20 A further object of my invention is to provide a process for switching railroad cars which will quickly classify cars in a minimum amount of time and with a minimum amount of labor.

25 A further object of my invention is to provide a process for switching railroad cars which will reduce the number of locomotives necessary for the switching operations to a minimum.

30 A further object of my invention is to provide a process which makes use of a simple, efficient, and economical car propelling means which may be readily installed in any switch yard, and which, when installed, 35 will not prevent the yard from being used in the ordinary way.

A further object of my invention is to provide a railroad car lifting and carrying device which is adapted to first raise the car 40 from the track, and to then convey the car to any track desired, and to then lower the railroad car onto the desired track.

A further object of my invention is to provide a car moving means which is adapted 45 to move a railroad car in any direction desired from a predetermined point.

Other objects and advantages will appear in the following specification, and the novel features of the invention will be particularly 50 pointed out in the appended claims.

My invention is illustrated in the accompanying drawings, forming part of this application, in which

Figure 1 is a diagrammatic view of a switch yard, showing one embodiment of my method operatively applied thereto,

Figure 2 is a side elevation of one form of a car lifting and carrying means,

Figure 3 is a plan view of the car moving means, and

Figure 4 is an enlarged section taken along the line 4—4 of Figure 3.

One means for conveying a railroad car from one track to the other, by lifting the same and placing it on the desired track, is shown in Figure 2. It will be noted that any means for moving a car from one track to the other, by lifting the same, would be sufficient for the purpose intended, and I therefore do not wish to be confined to the present means. A bridge 1 extends at right angles across the tracks of the yard, and is supported by uprights 2, which in turn are mounted on pedestals 3. The bridge 1 carries a traveling crane 4, the crane having 75 downwardly depending arms 5, which are adapted to engage with the under side of all the journal boxes 6 of a freight car 7, or the like, so as to lift the same when the arms 5 are raised vertically by pinions 9. The arms 5 are pivoted to racks 8, confined in vertical slides (not shown), which are adapted to be actuated vertically by pinions 9, the pinions in turn being rotated by means not shown, so as to raise or lower the racks 8 at will. A 80 drum 10 is also carried by the crane 4 and has cables 11 wound thereon, the cables being connected to the free ends of the arms 5. It will be apparent that when the drum 10 is rotated, it will swing the arms 5 about 90 their pivots 12 so as to operatively engage with the freight car 7, or disengage from the freight car 7, and swing to the horizontal position in plane of the pivots 12. The automotive crane 4 is carried and driven in either direction by wheels 13, which in turn are carried by the bridge or support. The crane 4 may be controlled by a controller 14, which is disposed in the operator's cage 15. It will be apparent from this construction that the 100 car 7 may be lifted from the track 16 and be conveyed to any track parallel therewith, such as the track 17, and then be lowered onto the track 17.

After the car has been lowered onto the 105 desired track, it may be moved in either di-

rection by any means, such as the means disclosed in Figures 3 and 4. This means comprises a pressure cylinder 18 which is disposed beneath the track 17 so as not to obstruct the passage of railroad cars thereover. A suitable runway, such as one composed of two channel irons 19, and an I-beam 20 disposed therebetween, is placed between the two rails of the track 17. A car moving device or catapult 21 is disposed in the runway formed by the channel irons 19 and the I-beam 20. This device may be of any construction, such as that shown in Figure 4, in which the bumper 22 is carried by an upright 23, the latter being secured to a frame 24. The frame 24 is provided with rollers 25 at the sides thereof which are adapted to be received in the channel iron 19 and in the I-beam 20. The device 21 is connected by means of a cable 26 to a fixed pin 27, or the like. The cable is also passed around a pulley 28 which is carried by the piston rod 29 of the cylinder 18. It will therefore be apparent that when the piston 30 is moved from the position shown in Figure 3 towards the opposite end of the cylinder, it will move the device 21 toward the cylinder. A valve (not shown) is adapted to control the amount of fluid which enters the cylinder, and to thereby control the speed of the device 21 along the tracks 17. The device 21 is moved slowly until the bumper 22 engages with the car 7, and then the device is quickly accelerated until the car is going at the desired or sufficient speed. This speed may be varied so as to make the car coast for any desired distance. A train-rider may ride with the car and apply the brake carried by the car so as to bring the car to a stop when it is in the desired place. It will be noted in Figure 3 that two of the devices 21 are provided for each track and are adapted to move the car in either direction along the track. These devices are independent units, and either one may be omitted from installation if desired. The device 21 is brought back to its first position, or its starting point, by means of a drum 31, around which a cable 32 is wound, the free end of the cable being secured to the device 21.

It will be obvious that when one of the bumpers or devices 21 is used to move the car, the car would strike the other bumper unless that bumper was thrown out of operative position. To this end, I turn the channel iron 19 and the I-beam 20 downwardly adjacent to the starting point of the device 21 so that when the device is in this position, the top of the device will be positioned below the top of the rails 17 (see Figure 4). In other words, when the devices 21 of the track are in normal position of rest, they will be disposed below the rails 17 and the track may therefore be used for ordinary

purposes. When the device is actuated, it is first brought upwardly so as to position the bumper 22 in alinement with the bumper 33 or some other suitable portion of the car so that the bumper 22 will come into contact with the bumper 33 when the device is moved into engagement with the car.

From the foregoing description of the various parts of the device, the operation thereof may be readily understood. It will be noted that when the crane 4 is on the extension of the bridge beyond the outside of the track, and the devices 21 of each of the tracks are in inoperative position, all of the tracks may be used in the ordinary manner. Assume that a train of cars 34 enters the yard, and it is desired to "classify" the cars. Some of the cars in the train may be rush orders, some may have perishable goods in them, some may be hold orders, some may need repairs, and the rest may need be classified in various classifications. With my improved process, the cars may be quickly transferred from one track on which they enter to the desired track or tracks and into desired relative positions in train on new track, without the necessity of using either the switches and ladder tracks of the yard, and without using more than a single switch locomotive. The car desired to be transferred from the track which it is on to the desired track, is brought beneath the bridge 1 so as to permit the crane 4 to lift the same and to carry it to the desired track. In the diagrammatic view in Figure 1, I have shown a typical terminal in which two of the tracks 35 are for hold orders or for repairs, in which another set of tracks 36 are for making up trains of various classifications, and in which the set of tracks 37 may be used for any other purpose desired. I also show a track 38 which has no connection with the yard, such as by switches or the like, and which, with my process, any of the cars of the yard may be readily transferred to or from the track. It will further be apparent that while classifying the cars to their various tracks by my process, the ladder track and switches are clear and may be used for unrelated movements at the same time. In other words, the tracks that are not being used to receive the cars from the train 34, may be used to receive other trains, or for any other purpose desired, and cars already classified may be drawn from any track without interfering with continuous operations of classification. The bridge 1 is preferably, but not necessarily, disposed some distance from either end of the yard, and in such case, divides the yard into practically twice the number of classification tracks as there are tracks in the yard. For instance, if ten tracks are in the yard, a train may be sub-divided into nineteen classifications, since the track on which the train

enters may be used for one classification, and the other tracks may each be used for two classifications.

In case of terminal congestion, the cars 5 may be transferred from one track to the other with practically the same facility as if the yards were empty. This is due to the fact that all switching over ladder tracks in classifying is obviated, and the cars are 10 transferred from one track to the other in one operation. The classifying of a car in a single operation reduces the travel of the car in the yards to a minimum, and also reduces the damage of the car and load due 15 to bumping, or the like. The device may be used with a yard of any size, and as many of the devices as desired may be used in a single yard. Thus, if a yard has forty or more tracks, it may be provided with two 20 bridges which will span twenty tracks, or with four bridges which will span ten tracks, etc. The size of the yard makes no difference as to the operation of the device, since the switching locomotives are largely done 25 away with, in classification work, thereby obviating the increased length of travel of a car when moved from one track or train to another by a switch locomotive in a large yard. When a train of one classification has 30 been made up, the train may be removed from the yard, while the device is still classifying cars for other trains. Furthermore, the number of trips per man day of the car 35 riders is greatly increased, since they have no dead travel along ladder tracks in either direction, the yard is only half as wide, and cross movement is unobstructed. This is not the case in the ordinary yards, since the 40 train of cars has to be sent down one track so as to release one car, and then be sent back on the same track, and then be sent forward on another track so as to release a second car. With the present device, only one 45 car is moved at a time. It will also be observed that collisions between various freight cars are reduced to a minimum, since the cars are moved without the use of switches, thus avoiding collisions between 50 the switching locomotives or cars and the other locomotives which move through the yard. As heretofore stated, the train may enter any track and be classified therefrom. There are really only three movements to 55 the classification of a car, namely: the disposing of the car on receiving track under the bridge and freeing the car from its train, the transferring of the car from the track which it is on to the desired track, and the moving of the car in either direction along 60 the track on which it is disposed. It is obvious that these three operations may be taking place at the same time on three different cars, thereby greatly increasing the efficiency of the system and of the yards. 65 The rush orders, hold orders, or cars for re-

pairs may be instantly removed from the train with which they enter and be disposed on the desired tracks.

The device may be readily installed in any yard, and will not interfere with the normal operation of the yard by ordinary methods, since, as heretofore stated, the crane 4 may be placed in inoperative position or beyond limit of the tracks, and the moving devices 21 are normally disposed in inoperative 70 position, thus freeing the tracks for ordinary switching purposes. One end of the crane is shown, but the two ends of the said crane are similarly equipped with elements 5, 8, 9, 10, and 11, as shown in Figure 2. 80

As heretofore stated, it is to be noted that the specific means shown in the drawing for transferring a car from one track to the other, and for moving a car on the desired track, is not essential to the operation of the 85 device. Any means for transferring a car from one track to the other and for moving the car on the track, would be sufficient for the purpose intended. I therefore do not desire to be confined to the specific means 90 for accomplishing the required switching.

It will be apparent from the foregoing that by applying this process to any yard, the classification of the cars from one train to another may be accomplished with great 95 rapidity, thus reducing the travel of the cars in the yard to a minimum, and obviating yard congestion.

I claim:

1. The herein described process for switching railroad cars which consists in moving a car laterally from one track to a second track, and propelling the car in either direction on said last named track to the desired position thereon. 100

2. The herein described process for switching railroad cars which consists in lifting a car from a train of cars on one track, conveying the car to a second track, propelling the car on said last named track to the desired position thereon, lifting a car from a train of cars on a third track, conveying said last named car to said second named track, and propelling said last named car on said second named track to a position adjacent to said first named car. 110

3. The herein described process for switching railroad cars which consists in lifting a car from a train of cars on one track, conveying the car to a second track, propelling the car on said last named track to the desired position thereon, lifting a car from a train of cars on a third track, conveying said last named car to said second named track, and propelling said last named car on said second named track to a position opposite to the movement of said first named car. 115

4. The herein described step in a process for switching railroad cars which consists in 120

stationary means for propelling the car along the track in either direction from a given point.

5. The herein described process for switching railroad cars which consists in lifting the car from the track, conveying the car to the desired track, lowering the car onto the desired track, and propelling the car in either direction along the track to the desired position.

6. In a car switching means, a guide member disposed between the rails of a track, a car moving device movably carried by said guide member and being adapted to move in the direction of the track, and a cylinder having a piston therein, said piston being operatively connected to said car moving device, whereby said device is moved when said piston is actuated.

20 7. In a car switching means, a guide member disposed between the rails of a track, a car moving device movably carried by said guide member, a cylinder having a piston therein, said piston being operatively connected to said car moving device, whereby said device is moved when said piston is actuated, a cable secured to said car moving device, cable actuating means, said guide member being curved downwardly adjacent to one end of the travel of said car moving device, whereby said car moving device is drawn below the level of the track when moved in the curved portion of said guide member.

35 8. The herein described process for switching railroad cars which consists in lifting a car from a train of cars on one track, conveying the car to any one of a plurality of tracks which are disposed parallel to the first named track, propelling the car on the second track in either direction to the desired position thereon, lifting a second car from said first named track or from any other track and conveying the car to said second named track or any other track, and propelling the second car in either direction on said last named track.

9. A car moving device comprising a frame adapted to straddle a plurality of parallel tracks, a car lifting crane movably carried by said frame, vertical racks carried by said crane and adapted to be moved in a vertical plane, arms pivotally carried by the lower ends of said racks, said arms being adapted to extend over the ends of a freight car, cross beams secured to the free ends of said arms and being adapted to engage with

the journal boxes of the car, means for moving said racks upwardly, and means for swinging said arms outwardly.

10. A car switching means comprising three guide members disposed between the rails of a track, two car moving devices slidably carried by said guides, and being adapted to move cars in opposite directions along the track, two cylinders having pistons therein, said pistons being connected to the devices, and being adapted to move the devices in opposite directions along the track.

11. The herein described process for switching railroad cars which consists in lifting a car from one of a plurality of parallel tracks, conveying the car to any one of the tracks, propelling the car on the second track in either direction to the desired position thereon, lifting a second car from any one of the tracks, conveying the second car to any one of the tracks, and propelling the car on the last named track in either direction to the desired position thereon.

12. The herein described process of switching cars to make up trains which consists in picking up and moving laterally individual cars from the track and in propelling the moved cars successively to the positions desired in the made up train.

13. The herein described process of switching or classifying railroad cars, which consists in lifting any desired car detached from the adjacent cars within the train, conveying the detached car to a desired track, lowering the car onto the desired track, and propelling the car in either direction along the track to a desired position.

14. A car moving device comprising a frame adapted to straddle a plurality of parallel tracks, a car lifting crane movably carried by said frame, vertical racks carried by said crane and being adapted to move in a vertical plane, arms pivotally carried by the lower ends of said racks, said arms being adapted to extend over the ends of a freight car, cross beams secured to the free ends of said arms and being adapted to engage with the journal boxes of the car, pinions engaging with said racks for actuating the latter, a drum, and cables wound on said drum and being connected to the free ends of said arms for swinging said arms out of engagement with said car.

FRANK W. EAGELSTON.
